ROOM DEODORIZER

John S. Levey, Westlake Village, Calif., assignor to Days-Ease Home Products Corp., North Hollywood, Calif.

Filed May 15, 1972, Ser. No. 253,686

Term of patent 14 years

Int. Cl. D23—04

U.S. Cl. D23—150

FIG. 1 is a front perspective view of a room deodorizer showing my new design;

FIG. 2 is a side perspective view thereof, the opposite side of the simulated pot being a mirror image of the side shown;

FIG. 3 is a top plan view thereof.

I claim:

The ornamental design for a room deodorizer, as shown and described.

2,810,176 10/1957 Gaafar.

2,984,045 5/1961 Eggan.

3,400,890 9/1968 Gould ----- 239—36
